UNITED STATES PATENT OFFICE.

WILLIAM ROEMER, OF NEWARK, NEW JERSEY.

IMPROVEMENT IN BUCKLES.

Specification forming part of Letters Patent No. 131,028, dated September 3, 1872.

To all whom it may concern:

Be it known that I, WILLIAM ROEMER, of Newark, in the State of New Jersey, have invented a new and useful Improvement in "Buckles," of which the following is a specification:

My invention relates to that class of buckles used for ladies' or children's waist-belts; and consists in the arrangement of a hook on one end of the belt to be hooked into the tongue-bolt of the buckle.

Figure I represents a front view of a buckle embodying my invention. Fig. II shows a longitudinal section of the same, with the ends of the waist-belt.

A is the buckle, to which the tongue-bolt *m* is attached, carrying one or more tongues, *a*, constructed in the usual manner. This buckle, of which the part A is generally made ornamental and fancy, and very often of paper, leather, or any other material, in imitation of more valuable material, is attached to one end, D, of the waist-belt. B is a plate, riveted, by means of the rivets *v*, to the other end D', of the waist-belt. When the buckle is made with only one tongue, *a*, as here represented, two hooks, *n*, are made on the outer end of this plate B, hooking into the tongue-bolt *m*. When the buckle is made with two tongues, either one hook is made on the end of the plate B,

hooking on the tongue-bolt between the tongues, or three hooks may be made to take hold of the tongue-bolt, between and above and below the tongues.

By this means the fastening of the belt is made more simple, and the plate B or the end D' of the belt, covering the tongue-bolt and end of the tongue, gives a smoother surface and prevents the tearing of the dress.

I am aware that imitation buckles have been before attached to one end of a waist-belt, and a hook or hooks made at the other end to fasten the belt together; but in all cases an extra bar or loop was fastened to the tongue-bolt, into which this hook was hooked, making thereby this fastening more complicated, and causing the dress, by the continued friction, soon to wear out.

What I claim as my invention, and desire to secure by Letters Patent, is—

In combination with the tongue-bolt *m* in buckles for ladies' waist-belts, a plate, B, with one or more hooks, *n*, when said hooks are hooked directly on said tongue-bolt, substantially as and for the purpose herein set forth.

WILLIAM ROEMER.
